UNITED STATES PATENT OFFICE.

CARL L. CHRISTENSEN, OF DALTON, NEBRASKA.

FAN.

Application filed October 10, 1925. Serial No. 61,868.

This invention relates to improvements in motor vehicle power plants which embody internal combustion engines that are water cooled, and wherein the cooling water is 5 reduced in temperature by passing through an air cooled radiator.

In power plants of the above kind the air is usually drawn rearwardly through the radiator by means of a fan driven by the 10 engine and disposed directly behind the radiator and in front of the engine. The fans now commonly employed embody blades having a fixed pitch and adapted to draw the air rearwardly through the radiator to 15 wards the engine.

It is well known that the engines of power plants of the above kind do not operate with maximum efficiency during cold weather by reason of the fact that the fan maintains 20 the cooling water at an excessively low temperature. It is also well known that the fan now employed often results in freezing of the water in the radiator during cold weather so that the water cannot circulate, 25 and overheating of the engine results. It is still further well known that power plants of the above kind often become faulty in operation by reason of the fact that the water is kept at such a greatly reduced tem- 30 perature that starting of the engine is only effected with great difficulty.

The primary object of the present invention is to provide means operable for varying the amount of air drawn through the radiator in accordance with the variations in climatic conditions and temperature encountered whereby the water will not be unduly cooled in cold weather but may be maintained at a proper temperature for most 35 efficient operation of the engine.

Still another object of the invention is to provide means for discontinuing the forcible draft of air through the radiator whereby the liability of the water freezing in the 40 radiator in very cold weather is reduced to a minimum.

Still another object of the invention is to provide means for forcing the warm air from about the engine forwardly through 45 the radiator, so as to have a warming effect upon the water in its passage through the radiator whereby starting of the engine is facilitated and the efficiency of the engine is enhanced during abnormally cold weather.

55 I preferably accomplish the above objects by the provision of a fan between the en-

gine and the radiator embodying blades reversible in pitch and adjustable in pitch so as to effect the desired draft of air in the desired direction.

A further object is to provide a fan of the above kind which is extremely simple and durable in construction as well as efficient in operation.

Still another object of the invention is to 60 provide a fan of the above kind wherein means is provided for facilitating ready control of the blades thereof by the driver of the vehicle.

Further objects will become apparent as 70 the nature of the invention is better understood and the same consist in the novel form, combination and arrangement of parts hereinafter more fully described shown in the accompanying drawing and claimed.

In the drawing, wherein like reference characters indicate corresponding parts throughout the several views.

Figure 1 is a fragmentary elevational view illustrating an embodiment of the present invention.

Figure 2 is a front elevational view partly broken away, of the fan shown in Figure 1.

Figure 3 is a central longitudinal section of the fan shown in Figure 2.

Figure 4 is a transverse section taken on line 4—4 of Figure 3.

Figure 5 is a transverse section taken on line 5—5 of Figure 3.

Figure 6 is a transverse section taken on line 6—6 of Figure 3.

Referring more in detail to the drawings, 5 indicates a conventional form of water cooled internal combustion engine and 6 indicates a conventional form of air cooled radiator through which the water is circulated 10 from the water jacket of the engine in a well known manner, the radiator 6 being spaced from and in front of the engine.

In the embodiment of the invention shown, 100 a horizontally and longitudinally disposed spindle is fixed to the cylinder block of the engine 5 by having its threaded rear end 7 screwed into a threaded socket in the forward end of the engine block. The spindle 7 terminates at its outer end in a head 8 against which is positioned the forward end of a pulley 9 which is rotatably disposed upon the forward end of the spindle 7. The pulley 9 has a hollow rigid extension upon 105 its forward end forming the hub 10 of a fan which also embodies a plurality of radial

2

blades 11, which have shafts 12 upon their inner ends journaled in radial openings of the hub 10 whereby the fan blades may rotate about their longitudinal axes. Secured upon the inner ends of the shafts 12 of the blades within the hollow hub 10 are spur gears or pinions 13, and slidable longitudinally through suitable openings in the pulley 9, are a plurality of rods 14, the forward ends 10 of which terminate in rack bars that project into the hub 10 and each of which meshes with one of the pinions 13 of the fan blades 11. Slidable longitudinally of the spindle rearwardly of the pulley 9 is a collar 15 to which the rear ends of the rods 14 are rigidly secured, and this collar 15 has an annular groove engaged by the inwardly projecting pins 16 on the ends of a fork 17, provided upon one end with a lever 18, which 15 is pivoted intermediate its ends as at 19 upon the horizontal arm of an angular bracket 20 suspended from the rear end portion of the spindle 7 as clearly shown in Figures 1 and 3. A bushing 21, is disposed on the spindle between the bracket 20 against the engine block. The collar 15 is slidable on the bushing 21, and it is thus apparent that when the collar 15 is forced in one direction the pinions 13 are turned to adjust the pitch of the blades 30 11 in one direction while movement of the collar in the other direction effect adjustment of the pitch of the blades 11 in a reverse direction. In this manner the blades may be set in a plane at right angles to the axis of rotation of the fan so as to be neutral and have no action upon the air in so far as drawing or forcing the same through the radiator is concerned. Upon movement of the collar 15, in one direction, the rack bars of the rods 40 14 cause rotation of the pinions 13 for effecting rotation of the blades 11 about their longitudinal axes, and it is thus apparent that the blades may be set at the desired pitch for effecting the drawing of the required amount of air rearwardly through 45 the radiator. On the other hand, movement of the collar 15 in the opposite direction will effect a reverse rotation of the gears 13 so that the blades 11 are set at the desired pitch 50 in a reverse direction for regulating the amount of air forced by the fan forwardly through the radiator. The heat of the engine will warm this air and when the same is forced forwardly through the radiator 55 such air will have a warming effect upon the water passing therethrough for facilitating

starting of the engine or increasing its operating efficiency in abnormally cold weather as is obvious.

An operating rod 22 is connected to the lower end of the lever 18 and may be extended rearwardly to the instrument board of the vehicle so as to be conveniently manipulated by the driver of the vehicle.

The forward end of the hub 10 may be closed by a removable cover plate 23, held in place by set screws 24, and this cover plate may be removed for facilitating access to the pinion and rack bars for renewal or repair purposes.

From the foregoing description it is believed that the construction and operation as well as the advantages of the present invention will be readily appreciated by those skilled in the art.

70 Minor changes may be made without departing from the spirit and scope of the invention as claimed.

75 What I claim as new is:

A fan for motor vehicle cooling systems including a stationary spindle, a pulley rotatably disposed on the forward end of the spindle and provided with a plurality of passages therethrough disposed about and parallel with said spindle, a hollow hub rigid with the forward side of said pulley, a plurality of rods slidable longitudinally in said passages and having their forward ends projecting into the hub forward ends of said rods being formed to set up rack teeth, radial blades having longitudinal pivot elements upon their inner ends journaled in and projecting into said hub, pinions fixed on the inner ends of said pivot elements within the hub and each meshing with the rack teeth of one of said rods, a collar rotatable about and slidable longitudinally of the spindle rearwardly of the pulley and having the rear ends of said rods fixed thereto, means to adjust the collar longitudinally of the spindle, said spindle having a head upon its forward end substantially engaging the forward side of the pulley within the rear end of the hub, and means to maintain the pulley substantially in engagement with said head including a sleeve disposed on the spindle with its forward end abutting the rear side of the pulley, said collar being rotatably and slidably fitted on said sleeve.

100 105 In testimony whereof I affix my signature.

CARL L. CHRISTENSEN.
